(57) **CLAIM**

I claim the ornamental design for a DOT-compliant scrolling advertisement cabinet, as shown and described.

DESCRIPTION

FIG. 1 is a perspective view of a DOT-compliant advertising scroller cabinet, showing my new design in a closed configuration;

FIG. 2 is a front elevational view of FIG. 1;

FIG. 3 is a rear elevational view of FIG. 1;

FIG. 4 is a right-side elevational view of FIG. 1, the left-side elevational view being a mirror image thereof;

FIG. 5 is a top plan view of FIG. 1;

FIG. 6 is a bottom plan view of FIG. 1; and,

FIG. 7 is a perspective view thereof, illustrated in a partially open position.

The broken lines showing a truck in FIG. 1 depict environmental matter and form no part of the claimed design. The remaining broken lines depict the design as having no specific width.
